FOREIGN PATENT DOCUMENTS

FR 1 367 488 6/1964

1 Claim, 7 Drawing Sheets

FIG. 1 is a bottom perspective view of the palm side of a left-handed embodiment of a glove showing my new design, it being understood that a right-handed glove is a second embodiment, the only difference being that it is a mirror image thereof and of the following views shown;
FIG. 2 is a top perspective view of the back side of the glove illustrated in FIG. 1;
FIG. 3 is a bottom plan view thereof;
FIG. 4 is a top plan view thereof;
FIG. 5 is a left side elevational view thereof;
FIG. 6 is a right side elevational view thereof;
FIG. 7 is a front elevational view thereof;
FIG. 8 is a rear elevational view thereof; and,
FIG. 9 is a view similar to FIG. 5, except that some of the glove's finger tip portions are depicted in an open position to accommodate the wearer's fingers which are shown in phantom and which form no part of the claimed design.
The broken lines shown on the glove are understood to represent stitching.
